UNITED STATES PATENT OFFICE.

WILLIAM T. MAKEPEACE, OF BARNSTABLE, MASSACHUSETTS.

DESIGN FOR A CRANBERRY-SCOOP.

SPECIFICATION forming part of Design No. 27,815, dated November 2, 1897.

Application filed August 14, 1897. Serial No. 648,332. Term of patent 14 years.

To all whom it may concern:

Be it known that I, WILLIAM T. MAKEPEACE, of West Barnstable, in the county of Barnstable and State of Massachusetts, have 5 invented a new and original Design for Cranberry-Scoops, of which the following is a specification.

Referring to the accompanying drawings, Figure 1 is a top plan view, Fig. 2 a bottom 10 plan view, and Fig. 3 a side view, of a cranberry-scoop showing my new design.

As shown in the drawings, the leading or material feature of my design consists of the transversely-arranged trough-shaped and exteriorly-curved bottom of the berry-receiving 15 chamber at the rear of the scoop and the upwardly - curved tines at the front thereof, a being the transversely - arranged trough-shaped and exteriorly-curved bottom of the 20 scoop, a' a cross-bar at the front thereof, and

a^2 the upwardly and forwardly curved tines.

a^3 a^4 are the side pieces of the scoop, a^4 the top of the berry-receiving receptacle, and a^5 the handle.

a^6 and a^7 are cross-bars connecting side 25 pieces a^3 a^4 , handle a^5 being secured thereto.

Having described my invention, what I claim as new, and desire to secure by Letters Patent, is—

The design for a cranberry-scoop, as herein 30 shown and described.

In testimony whereof I have signed my name to this specification, in the presence of two subscribing witnesses, on this 10th day of August, A. D. 1897.

WILLIAM T. MAKEPEACE.
